UNITED STATES PATENT OFFICE.

BRENCHLEY ERNES GEORGE MITTELL, OF IVER, ENGLAND, ASSIGNOR TO VICTOR TALKING MACHINE COMPANY, A CORPORATION OF NEW JERSEY.

CONTROL FOR WIRELESS RECEIVING SETS AND OTHER ELECTRICAL APPARATUS.

Application filed November 18, 1924, Serial No. 749,789, and in Great Britain December 5, 1923.

This invention relates to improvements in controls for wires receiving sets and other electrical apparatus, the object of the invention being to provide a single control by means of which the variable components of the apparatus may be adjusted as required simultaneously. In the case of a wireless receiving set for example the object is to provide means whereby the various components of the apparatus, such for example as condenser, inductances, couplings and the like may be adjusted as required simultaneously by means of a single control.

As a general rule these various components of the apparatus are operated through separate control knobs, owing to the fact that, to give the required result, each component requires to be revolved through a different angle. In existing apparatus, where it has been proposed to effect simultaneously, by means of a single control, the adjustment of two or more variable components, it has been necessary to make one or more of the variable components of an unusual and complicated shape or design in order to give the result desired.

According to the present invention therefore, instead of attempting to match up all the electrical characteristics of the components of a receiving set for example, I give to each the movement which it requires by means, such as cams or equivalent devices, actuated from a single control member and designed to impart to the components dissimilar or irregular rates of movement. By this means it is made possible to graduate a control wheel uniformly with markings corresponding to wave lengths and to design all the components with great mechanical and electrical stability and of standard pattern, to employ valves of uniform characteristics and to ensure the supply of correct voltages to the filaments and anodes.

Further, according to the present invention, apart from a separate tuning device for giving the aerial of a wireless receiving set a standard value once and for all when the receiving apparatus is installed (though this will not be required if a so called aperiodic aerial is used), only one control member will be used for tuning all or any of the components of the set and by the movement of this single control, through suitable means, the variable components will be moved simultaneously, so as to vary the electrical value of two or

more components in predetermined relationship to one another. A single control enables a spindle to be revolved, from which spindle the several variable components will be moved to the extent in each case required. By these means for example one component of the apparatus may be adjusted for the purpose of tuning while a second component is adjusted to an electrical value bearing a predetermined relationship to the frequency to which the apparatus is tuned.

The means employed for giving the desired movement to the several variable components are preferably cams adapted to be rotated by the movement of the control member. Thus a cam so rotated may move one member of a variable electromagnetic coupling relatively to the other member of said coupling while a second cam varies the electrical value of a second variable component such as a condenser.

It has also been found convenient, instead of using a single aerial inductance coil to operate over the whole wave length range which the apparatus is intended to cover, to use a number of inductance coils which are brought into circuit with the aerial in turn, each of which is operative in conjunction with a single reaction coil for a portion of the whole wave length range.

It may happen that local conditions under which a set is being used are such that alterations in the standard setting of the reaction coil, for example, are required at some particular wave length settings. If for example the set were installed near to one particular transmitting station from which it was desired to receive, the signals from that station would in the ordinary way be too strong. This may be conveniently effected by locally enlarging or recessing the reaction coil actuating cam.

In the accompanying drawings, the invention is illustrated as applied to a control for a wireless receiving set in which, by the rotation of a single control member the reaction is varied simultaneously with, and in the desired relationship to, the frequency to which the apparatus is tuned.

Fig. 1 is a plan view of the apparatus, the top plate upon which the various components are mounted being removed, but its position shown in dotted lines.

Fig. 2 is an elevation in the direction of the arrow A in Fig. 1.

Fig. 3 is a sectional elevation on the line A—B in Fig. 1.

Fig. 4 is a sectional elevation on the line C—D in Fig. 1.

Fig. 5 is a sectional elevation on the line E—F in Fig. 1.

Fig. 6 is a part plan view of the top of the cabinet in which the apparatus is mounted.

Fig. 7 is a diagram of the electrical connections which may be used with the apparatus illustrated in Figs. 1 to 6, comprising one detector valve 78, and two magnifying valves 79 and 80.

All components are shown in the same relative positions in all the figures and the same component is designated by the same reference cipher throughout.

1 is the plate upon which the various components are mounted. 2 is a knurled wheel integral with which is formed a pinion 3. These are rotatably mounted upon a bolt 4 which screws into a bracket 5 mounted upon the plate 1 by screws 6. Another pinion 7 of the same size as pinion 3 and engaging therewith is rotatably mounted upon a pin 8 carried on the bracket 5, and the pinion 7 also engages with a toothed wheel 9 of large diameter (Fig. 2) which is mounted by means of distance pieces 10 and screws 11 upon the rear face of a wheel 12. The wheel 12 acts as an indicator and suitable markings are engraved upon its rim, such as wave lengths and the names or call signs of transmitting stations. The wheel 12 is rigidly mounted upon a shaft 13 which is capable of rotation in three bearings carried in three brackets 14, 15, 16 projecting downwards from the underside of the plate 1 and cast integral with it.

An ebonite flange 17 is rigidly mounted upon the shaft 13 and carries four circular ebonite boxes 18, 19, 20, 21 (Fig. 3). In these four boxes are carried four inductance coils having different inductances the total wave length range being divided into four parts each accommodated by one of the four inductance coils. The two ends of each coil are brought out to corresponding insulated segments of a commutator mounted upon the face of the flange 17. Thus in Fig. 3 the two ends of the inductance coil contained within the box 19 are connected to the segments 22 and 23 respectively. Contact is made with the segments by brushes 24, which are fastened by screws to an ebonite block 25 which is in turn fastened to the bracket 14 by screws 26 (Figs. 1 and 2).

Rigidly fastened to the shaft 13 is also a toothed wheel 27 which engages with another toothed wheel 28 of the same size, rigidly fixed to a shaft 29 which is rotatably mounted in bearings carried in the bracket 15 and a bracket 30 also projecting downward from the plate 1 and cast integral with it. Upon the shaft 29 are also rigidly fastened two cam wheels, one of which, 31, will be referred to as

the condenser cam wheel, and the other, 32, as the reaction cam wheel.

Rotatably mounted on the shaft 13 is a member 38 carrying two projecting arms 39 and 40 the arm 39 carrying at its extremity a roller 41 which bears upon the edge of the condenser cam wheel 31 and the arm 40 carrying at its extremity a toothed segment 42 attached to it by screws 43. This toothed segment 42 engages with a pinion 44 rigidly attached to a shaft 44 carrying the moving vanes 46 of a variable condenser 45, the condenser being so constructed that its capacity is proportional to the square of the angle of rotation of the moving vanes. Rigidly fixed to the condenser shaft 44 is also a drum 47 having a groove 48 around its periphery, in which lies a chain 49 fastened to the drum 47 by a screw 50. The other end of the chain is fastened to a helical spring 51 which is anchored to a lug 52 fixed to the top plate 1. This spring 51 tends to return the moving vanes of the condenser to the position of minimum capacity and to keep the roller 41 in contact with the condenser cam wheel 31.

A bell crank lever 53 is rotatably mounted on a shaft 54 which is fixed in the bracket 15 and in a bracket 55 which projects downwards from the plate 1 and is cast integral with it. One arm 56 of the lever 53 carries a roller 57 which bears upon the edge of the reaction cam wheel 32. The other arm 58 of the bell crank lever 53 carries a toothed segment 59 which is fastened to the arm 58 by screws 60. The toothed segment 59 engages with a pinion 61 formed upon a member 62 which is rotatably mounted on the shaft 13. The member 62 has formed upon it a drum 63 and an arm 64. The drum 63 is provided with a groove 65 around its periphery in which rests a chain 66 fastened to the drum 63 by a screw 67 and at its other end fastened to a helical spring 68 which is anchored to the lug 52. The arm 64 carries a cylindrical ebonite box 69 which is fastened to it by means of a screw 70, and contains the reaction coil, the spring 68 tending to return the reaction coil to the position of maximum reaction and to keep the roller 57 in contact with the edge of the reaction cam wheel 32.

A partial plan view of the top of the cabinet containing the apparatus is shown in Fig. 6. The top panel 71 is provided with a slot 71^a through which a portion of the graduated wheel 12 is visible. A portion of the knurled wheel 2 projects through another slot 71^b in the panel 71. The device is adjusted to the required wave length by turning the knurled wheel 2 from right to left until the required value is indicated on the wheel 12 opposite to the arrow 72 on the panel.

The operation of the above described apparatus is as follows:—

We will consider the components to be in

the relative positions shown in the drawings. The knurled wheel 2 is turned from right to left in Figs. 1 and 6 (or counter-clockwise in the other figures) and the graduated wheel 5 12 together with the shaft 13, the ebonite flange 17 carrying the four inductance coils and the toothed wheel 27 are rotated in the same direction through the pinions 3 and 7 and toothed wheel 9. Coil 19, which may 10 for example cover a range of wave lengths from 500 to 1000 metres, is in circuit through its commutator segments 22, 23 and the brushes 24 and the condenser 45 is connected in parallel with it. The cam wheels 31, 32 15 are rotated in the opposite direction to the shaft 13 (that is clockwise) through the toothed wheels 27 and 28. The condenser cam wheel 31, acting upon the roller 41 causes the member 39 together with the toothed segment 42 to rotate in a counter-clockwise direction, thus turning the vanes of the condenser 45 in a clockwise direction or increasing the capacity. The rate at which the capacity is increased is determined by the shape 20 of the cams. Meanwhile the bell crank lever 53 is being rotated in a clockwise direction by the reaction cam wheel 32, thus causing the reaction coil 69 to revolve in a counter-clockwise direction in an orbit about the shaft 30 13. In the construction illustrated the reaction cam is so designed that the reaction coil moves in the same direction as the inductance coil which is in circuit but at a slightly less rate. The electromagnetic coupling between the reaction coil and the inductance coil is comparatively tight at the minimum wave length to which the particular inductance coil is tuned, and as the wave length is increased so the reaction coupling is loosened. 35

40 When the knurled wheel 2 has been rotated so far that the rollers 41 and 57 have reached crests 73 and 74 respectively (Fig. 3) on the cam wheels 31 and 32, the commutator segments corresponding to coil 19 are on the point of leaving contact with the brushes 24 and the set is tuned to the maximum wave length for this particular coil namely 1000 metres. A slight further rotation of the knurled wheel 2 now causes the commutator segments corresponding to coil 20, which may for example cover a range of wave lengths from 1000 to 2000 metres, to come into contact with the brushes 24, whilst the rollers 41 and 57 drop into hollows 75 and 76 in the cam wheels 31 and 32 respectively (Fig. 3), thus causing the condenser vanes to fly back under the influence of the spring 51 to the position of minimum capacity, whilst the reaction coil 69 is pulled back by the spring 68 45 to the position of maximum coupling with the coil 20 or such other relative position as is found to be suitable for the particular wave length setting.

50 I claim:

55 1. In a device of the class described includ-

ing a variable electromagnetic coupling, means for adjusting said coupling including a single control member, and means including a cam member operatively associated therewith adapted to move both members of said coupling at different rates relative to one another. 50

2. In a device of the class described including a variable electromagnetic coupling and a tuning device, a control member, means including a cam member actuated thereby for moving both members of said coupling at different rates relative to one another, and means including a second cam member actuated by said control member and adapted to vary the electrical value of said tuning device 80 in predetermined relationship to the variation of said coupling. 75

3. In a device of the class described, a variable electromagnetic coupling including a plurality of inductance coils adapted to be used for given portions of the wave length range, means for successively inserting said coils in circuit, a single reaction coil, means positioning said reaction coil so as to be coupled with that inductance coil which is in circuit, and a unit control for said first named and second named means. 90

4. In a device of the class described, a control member, a shaft actuated thereby, a plurality of inductance coils disposed about said shaft and revoluble therewith, a reaction coil rotatably supported on said shaft and coupled with one of said inductance coils, and a cam member operatively associated with said shaft and adapted to rotate said reaction coil 100 at a rate different from the rate of rotation of said inductance coils. 95

5. In a device of the class described, a control member, a shaft actuated thereby, a plurality of inductance coils disposed about said shaft and revoluble therewith, said coils being adapted to be used for given portions of the wave length range, means for successively inserting said coils in circuit, a reaction coil rotatably supported on said shaft and coupled with that inductance coil which is in circuit, and a cam member operatively connected to said shaft for rotating said reaction coil with said inductance coil but at a different rate, said cam being adapted to allow said reaction coil to return to starting position when the succeeding inductance coil is inserted in circuit. 110 105 115

6. In a device of the class described, a control member, a shaft actuated thereby, a plurality of inductance coils disposed about said shaft and revoluble therewith, said coils being adapted to be used for given portions of the wave length range, means for successively inserting said coils in circuit, a reaction coil 125 rotatably supported on said shaft and coupled with that inductance coil which is in circuit, and a cam member operatively connected to said shaft for rotating said reaction coil with said inductance coil but at a different 130

rate, the surface of said cam having portions corresponding to said inductance coils, said reaction coil passing from control of one portion of said cam to control of the succeeding portion when the succeeding inductance coil is inserted in circuit.

7. In a device of the class described, a control member, a shaft actuated thereby, a plurality of inductance coils disposed about said 10 shaft and revoluble therewith, said coils being adapted to be used for given portions of the wave length range, means for successively inserting said coils in circuit, a reaction coil rotatably supported on said shaft and coupled 15 with that inductance coil which is in circuit, a cam member operatively connected to said shaft for rotating said reaction coil with said inductance coil but at a different rate, the surface of said cam having portions corresponding 20 to said inductance coils, said reaction coil passing from control of one portion of said cam to control of the succeeding portion when the succeeding inductance coil is inserted in circuit, and a second cam member operatively 25 connected to said shaft for adjusting said tuning device, said second cam surface having portions corresponding to said inductance coils and adapted to adjust said tuning device so as to produce a substantially progressive 30 increase in wave length.

8. In a device of the class described, the

combination with a reaction coil, a plurality of inductance coils adapted to be coupled in succession therewith, and a tuning device, of a control member, and cam means actuated 35 thereby for adjusting said coupling and said tuning device in predetermined relationship to the proper values for the wave length indicated by said control member.

9. In an electrical apparatus for radio reception, a plurality of variable components including a variable coupling, a single control member, and adjusting means operatively connecting said control member with said variable components, said means being adapted 40 to move both members of said coupling at varying rates relative to one another and to adjust the other of said components at a varying rate in predetermined relation to the variation of said coupling. 50

10. In a radio apparatus, a plurality of variable components including a variable coupling, and means for adjusting said components simultaneously but at varying rates, including a single control member and cam 55 means operatively connecting the latter with said variable components, said cam means being adapted to move both members of said coupling at different and varying rates.

In testimony whereof I have signed my 60 name to this specification.

B. E. G. MITTELL.
